UNITED STATES PATENT OFFICE

ALFRED E. HUNT, OF NEW HAVEN, CONNECTICUT, ASSIGNOR, BY MESNE ASSIGNMENTS, TO REMINGTON RAND INC., OF NEW YORK, N. Y., A CORPORATION OF DELAWARE

INDEX OR FILE

Application filed July 27, 1925. Serial No. 46,397.

This invention relates to indexes or files, and more particularly to that class of indexes wherein a series of index elements are arranged upon a support in such a manner that 5 a marginal edge of each will be exposed to view. In some instances, it is desirable that these elements be detachably retained upon the support and be adapted to have additional cards or record-bearing members 10 mounted thereon.

More specifically this invention relates to an improvement of this type of index or file, whereby the individual index elements constitute holders for a plurality of record-bearing 15 members, which are arranged thereon in such a manner as to present to view a series of marginal edges whereon data may be placed and be readily referred to. It is desirable that such an arrangement be, to some 20 extent, self-indexing, especially when the index is to be used under conditions where changes and additions are frequently required, such as in telephone, telegraph, credit lists or the like. In some instances it is desirable 25 that the individual holders be releasably engaged by a frame or the like, so that the series of record-bearing members mounted thereon may be removed from the frame for reference purposes, without dis- 30 arrangement of the series. It is also desirable, in some instances, to provide holders of the above type which are adapted to engage a frame having holder-retaining means of such construction that the frame may be used 35 either to hold and retain a series of such reference-member holders, or a series of individual record-bearing members without the necessity of altering, adding parts to or taking parts from the frame.

40 The object of this invention, therefore, is to provide an index having the elements thereof of such construction and arrangement that the above desirable features and advantages will be obtained, which index or file will be 45 inexpensive to manufacture and efficient in use.

To these and other ends the invention consists in the novel features and combination of parts to be hereinafter described and 50 claimed.

In the accompanying drawings:
Fig. 1 illustrates an index or file embodying the features of this invention;

Fig. 2 is a section on line 2—2 of Fig. 1;
Fig. 3 is a rear view of one of the index ele- 55

ments shown in Fig. 1;
Fig. 4 is a section on line 4—4 of Fig. 3;
Fig. 5 is a section on line 5—5 of Fig. 1;
Fig. 6 is a front view of an index element 60 arranged to support a series of a modified form of record-bearing members;

Fig. 7 is a front view of a somewhat different arrangement of a series of the modified form of record-bearing member;

Fig. 8 is a plan view of a modified form of 65 record-bearing member, and

Fig. 9 is a front view of a holder or index element, supporting two series of other modified forms of record bearing members.

For the purpose of illustrating the features of my invention, I have selected a series of one form of overlapping index elements, having means to engage a frame and to cause a margin of each of the elements to be exposed to view when the same are mounted 70 in or upon said frame. The frame, in this instance, comprises a base or bottom portion 10, which may be the bottom of a drawer, the base plate of a panel or of a swinging-leaf of any desired type. The means for 75 holding the index elements 11 within or upon the frame is illustrated as comprising a strip 12 having oppositely directed flange portions 13 and 14, which are spaced from the surface of the base 10 an amount sufficient to allow 80 the engagement therewith of oppositely and laterally directed tongue portions 15 and 16, formed with or secured to the index element 11. The elements 11 are also provided with means to cause each succeeding one of a series to overlap a predetermined amount in order to expose a margin of each to view. 85 As illustrated, this means comprises the perpendicularly directed tongue portions 17 and 18. As shown in Fig. 5, the body portion of 90 one element 11, nests between the tongue portion 18 and the body of the next index element, which causes the overlap and exposes a margin thereof, as above noted. For 95 a more detailed description of the nesting 100

and over'ap features of the particular form of index element shown in the drawings, reference is made to the patent to Irving Fisher, No. 1,048,056, dated December 24, 1912. It should be understood, however, that aside from the use of this form of index element as the illustrative means upon which to base the description of my invention, the same is not limited to the particular form of element shown, but is adapted to be incorporated in and associated with other types of overlapping index elements, which are adapted to be arranged so as to expose a margin of each of a series to view.

15 The index element, card, panel or sheet 11 is formed from a single piece of material such as paper or cardboard and comprises a base portion 20 and a flap portion 21, interconnected by a suitable hinge connection 22.

20 The tongue portions 15 and 17, and 16 and 18, respectively, in this instance are integral and are struck out and directed rearwardly from the material forming the base portion 20. A series of elements 11, therefore, when mounted upon a holding frame 10, as above described, and before applying thereto the record-bearing members, would present to view the free margin 23 of each element.

25 The flap portion 21 of these index elements may be adapted by various arrangements to support and retain a series of additional members thereon, one arrangement for so doing being shown in Figs. 1 to 5, inclusive. In these figures, the index element 21 is provided with two pairs of spaced-apart parallel slits 24 and 25, and 26 and 27, respectively, whereby two series of additional record-bearing members 28 may be mounted thereon. The members 28, in this instance, are illustrated as being of the form of index elements corresponding to the above-mentioned patent, and are, therefore, provided with support-engaging and internesting means of a similar design. This means comprises the oppositely and laterally directed tongues 29, which in this particular form, have portions 30 thereof directed perpendicularly.

30 The laterally directed tongues 29, in this instance, are formed in such a manner that they are directed toward each other and are adapted to be slipped through the slits 24 and 25 or 26 and 27, respectively, and engage one of the portions 31 of the index element lying between the respective pairs of slits, as shown in Fig. 3.

35 The record-bearing members 28, by such engagement, are detachably retained upon the index element 11, and are substantially held thereon against lateral shifting or accidental removal therefrom in a forward direction, although being slidable lengthwise thereof. Each member 28 is nested between the tongue portions 30 of the overlying card and the 40 card body thereof, which due to the spacing

of this tongue portion from an edge of the member, causes an exposed margin to be presented to view.

45 Each of the slits 24 and 25, and 26 and 27, in this instance, terminate in an opening 32 formed in the index element 11 in such a manner that an upwardly directed edge 33 is presented which supports the lowermost member of the series of record-bearing members 28 by being engaged by the tongue portion 30 thereof and nested between the same and the body of the card. The entire series, therefore, is detachably supported against slippage vertically, as shown in Fig. 3. In order that the upper margin of the uppermost member of the series will not tend to bend outwardly, means is provided to retain the same closely associated with the surface of the index element 11. The means illustrated comprises diagonal slots or slits 34, which are adapted to receive a corner portion of each of the uppermost members of the series.

50 From the above description, it is apparent that an index has been provided wherein a supporting frame 10 is adapted, by index element engaging means, such as 12, or the like, to detachably engage and support a series of index elements of a form like 11, which in turn are adapted to engage and support a series of record-bearing index elements 28, or the like, which are detachably retained thereon. Each index element 11, with the series of members 28 secured thereto, may be removed from the frame and from the series of index elements thereon, and be replaced by an index element not provided with a series of members, such as 28, if it is so desired, and the frame 10 is adapted to as efficiently support the same as it did the element removed. In addition to this possible operation, any one of the individual members 28 may be removed from its supporting element and replaced by another of similar design.

55 Additions to the series of members 28 upon any one of the index elements 11 may be made at any time by removing the lowermost member of a series, for instance, the one designated Acme and inserting the member to be added in its proper alphabetical sequence. The member Acme so removed is placed at the top of the next series of members after removing the lower one of the same series, in this instance Aetna, which will be placed upon the underlying index element the lower margin of which is shown covered by the members 28, designated Ahern and Albert, respectively. By this method, the index developed by the use of the features of this invention may correctly be called self-indexing, for the user at a glance at the exposed margins of the members 28 which cover the extending margins 23 of the elements 11 may readily determine at all times what members are upon any one of the elements, without

uncovering the same. For instance, the third element of the series shown in Fig. 1 can be concluded to have record-bearing members mounted thereon in the left-hand series, all names of parties, or accounts, etc. included 5 between the alphabet letters ALB, see right-hand portion of element next above, and BAE the lowermost member at the left-hand margin of the third element. Likewise, the 10 right-hand series upon this element will be provided with all names, etc., of parties, or accounts, between the letters BAE and BEE, ending in Beebe. The insertion of a member in any series does not affect this self-indexing 15 as the lowermost member of each series at all times indicates the foregoing members thereof and also indicates the subsequent members of the next series.

Figs. 6, 7 and 8 illustrate the principles of 20 this invention when record-bearing members of another form are used. The form of member 40 shown in detail in Fig. 8, corresponds to the individual units of the interlocking type of index member shown in the patent to 25 Daniel A. Wilcox, No. 1,531,893, dated March 31, 1925. The cards are detachably retained together by the interlocking of the tongues 41, located adjacent a margin thereof, into the slots 42, in such a manner that the cards 30 overlap each other a predetermined amount to expose a portion thereof as at 43 to view. A plurality of members of this form is shown arranged in a series by such interlocking mounted upon index elements 44 and 45, respectively, in Figs. 6 and 7.

In Fig. 6 the series of members 40 are retained upon the element 44 by the engagement of the tongues 41 thereof with the element 44 within slits 46 provided therein. The tongues 41 are oppositely and laterally 40 directed and are readily inserted through the slits 46. By also extending toward each other in opposed relation, the tongues 41 engage the material of the index element 44 lying between the slits 46 and resist accidental removal and lateral shifting of the member upon the index element.

In Fig. 7 the portion 47 of the member 40, which lies between one marginal edge and a 50 slit or slot 42 at both the side edges thereof is used as the engaging means whereby the member is retained upon the index element 45. Slits 48 are provided in the element 45 into which the laterally and oppositely directed tongues or side edge portions 47 are 55 inserted. These tongues or portions extend laterally away from each other and, therefore, engage the material composing the element 45, lying between the slit 48 and the 60 side edge thereof.

The self-indexing feature above noted, regarding the form shown in Figs. 1 to 5, inclusive, is present in the arrangements and forms shown in Figs. 6 and 7, and the general 65 features of operation of the entire index

are also present. Each element 44 or 45 is detachably engageable with a frame by means of tongues 15 and 16, and the members 40 are detachable from the respective elements and capable of rearrangement thereon without 70 destroying the sequence thereof.

Two other slightly modified forms of record-bearing members are shown in Fig. 9, for convenience, both forms being illustrated mounted upon the same index element. The 75 index element 50 of this figure is provided with slits 51 arranged in a somewhat similar manner as those of the element 11, previously described. The members 52 and 53, respectively, are provided with somewhat similar 80 tongues 54 and 55, which have portions thereof analogous to the portions of the tongues of the member 28.

The tongues 54 provided in the members 52, shown in the left hand series, are formed 85 from the material of the member and are the means whereby the members are retained upon the element 50. Each of these tongues has a laterally directed portion, which portions extend in opposite directions relatively 90 to each other so that when they are inserted through the respective slits each will engage the index element upon a surface of the material composing the same, which lies between the slit and the side edge thereof.

The tongues 55 of the members 53 are similar to the above in respect to the engagement with the index element, but are formed to present one tongue for each member, this tongue having oppositely directed portions 100 57 and 58 thereon, which extend laterally away from each other. Instead of the corner slits 34 being provided to retain the uppermost card closely associated with the index element, ears 59, one for each such card, are 105 shown in this figure as the means for such use. The ears 59 are preferably struck up from the material forming the index element and engage over the center of the top edge of the members 52 and 53, as illustrated.

While I have illustrated and described some preferred forms of devices embodying my invention, I do not limit myself to the exact details shown, as many modifications and variations thereof are possible which 115 will lie within the spirit of the invention and the scope of the appended claims.

What I claim is:

1. In an index or file, a supporting frame having a series of overlapping index elements 120 detachably mounted thereon with a margin of each exposed to view, one of said elements having a plurality of series of record-bearing members detachably mounted thereon, the lowermost member of each series extending over the exposed margin of said element and adapted to bear insignia indicating the record matter upon the remainder of said members in the series.
2. In an index or file, a supporting frame 130

- having a series of overlapping index elements detachably mounted thereon with a margin of each exposed to view, one of said elements having a plurality of series of overlapping and interlocking record-bearing members 5 detachably mounted thereon, the lowermost member of one of the series extending over the exposed margin of said element and adapted to bear insignia indicating the record matter upon the remainder of said members.
3. In an index or file, a supporting frame having a series of overlapping index elements detachably mounted thereon with a margin of each exposed to view, each of said elements 10 having a plurality of series of overlapping and interlocking record-bearing members detachably mounted thereon, the lowermost member of one series extending over the exposed margin of each of said elements and 15 adapted to bear insignia indicating the record matter upon the remainder of the members upon each element, and those of an adjacent element.
4. In an index or file, a supporting frame 20 having a series of overlapping index elements mounted thereon with a margin of each exposed to view, one of said elements having a series of record-bearing members mounted thereon, in overlapped relation whereby a 25 margin of each extends beyond the body of another, the lowermost member of said series overlying the exposed margin of said element and adapted to bear insignia indicating the record matter upon the remainder of said members.
5. In an index or file, a series of index elements adapted to be supported in overlapping relation with a marginal portion of each exposed in visible index relation, a series of 30 record-bearing members detachably mounted on each index element, said index element having means for supporting the record-bearing member at one end of said series with a free marginal edge in substantially coincident 35 relation with the exposed marginal edge of said element.
6. In an index or file, an index element having means on one marginal portion for engaging a support and the opposite marginal portion free, a series of interengaged 40 record-bearing members detachably connected to said element, said element having means for cooperation with the record-bearing member at one end of the series to support said 45 member with a marginal portion overlying the free marginal portion of said element with the edges substantially coincident.
7. In an index or file, an index element having means on one marginal portion for engaging 50 a support and an opposite free marginal portion, a series of interengaged record-bearing members having means slidably and detachably engaging said element, means on 55 said element cooperating with the record-bearing member at one end of the series to

retain said member with a marginal portion overlying said free marginal portion of said element, and means on said element adjacent the first-mentioned marginal portion for engaging the edge of said record member at the opposite end of the series to retain said members against sliding movement thereon.

8. In an index or file, an index element having means on one marginal portion for engaging a support and an opposite free marginal portion, said element having slots terminating in openings spaced from said free marginal portion and in parallel relation thereto at their nearest edges, and a record-bearing member having means on one marginal portion detachably engaged in said openings, and having the opposite marginal portion overlying the free marginal portion of said element, the edges of the free marginal portions of said element and member being substantially coincident.

9. In an index or file having a plurality of index elements arranged in overlapping relation, to expose a free marginal portion of each, each index element comprising a sheet 20 provided with means at the opposite marginal portion for attachment to a support to mount said elements in offset overlapping relation thereon, said sheet having a pair of parallel slots extending substantially at right-angles 25 to said free marginal portion, and shoulders at the ends of said slots parallel to the edge of said free marginal portion, and a plurality of record-bearing members having a marginal portion of each formed with inwardly 30 projecting tongues and shoulders adjacent said tongues, each of said members engaging between the tongues and body of an adjacent member in nested overlapping relation, said 35 tongues engaging through the slots in said index element and securing said members thereto, one of said members having the shoulders thereon engaged with the shoulders on said element to support said member with its free marginal edge terminating substantially coincident with the free marginal edge 40 of said index element.

In witness whereof, I have hereunto set my hand this 16th day of July, 1925.

ALFRED E. HUNT. 115
